C. L. Stevens.

Railroad Tank Feeder.

N° 57.211.

Patented Aug. 14, 1866.

Inventor.

Chas L Stevens
By his
Attorney
G. B. Fowler

UNITED STATES PATENT OFFICE.

CHARLES L. STEVENS, OF GALESBURG, ILLINOIS.

IMPROVED METHOD OF ELEVATING WATER INTO RAILROAD-TANKS.

Specification forming part of Letters Patent No. 57,211, dated August 14, 1866.

To all whom it may concern:

Be it known that I, CHARLES L. STEVENS, of the city of Galesburg, in the county of Knox and State of Illinois, have invented a new and Improved Mode of Elevating Water into Railway-Tanks; and I do hereby declare the following to be a full, clear, and exact description of the construction and operation of the same, reference being had to the accompanying drawings, making a part of this specification, in which—

Figure 1 is a plan view of a rocking or movable rail-platform and its appurtenances connecting therewith for elevating water into railway-tanks; Fig. 2, longitudinal section of platform, as indicated by the line *x y* in Fig. 1, giving a side elevation of tank and pump-tubing in the rear; Fig. 3, views, in detail, of lock arrangement.

Like letters in the figures of the drawings indicate like parts.

The nature of my invention consists in operating a rail-platform on a series of compound levers, so arranged in their connection with the platform and shafts below the same as to give an easy rocking motion to the platform when railway-trains pass over the same, which motion, through the levers, is imparted correspondingly to the shafts having levers attached to their ends, which, connecting with vertical rods and fulcrum-levers on the tank-stand, operate the piston-rod of one of three pumps, as may be desired, and thereby elevate and fill the station-tank with water by reason of the trains performing the operation, instead of manual labor or other power.

I am aware of similar attempts having been made to accomplish the same purpose; but they have failed to attain the desired result in a satisfactory manner upon trial. A practical demonstration of this, however, has proved it to be a complete success, possessing advantages superior to anything that has heretofore been attempted in this line.

My invention further consists in so constructing the platform as to have the transverse end and center rods constituting the framing thereof project therefrom into slots or places cut out of the bed-sills, on which the track-rails rest, and immediately under the rails, having friction-rollers on their ends, whereby the said projecting ends of the rods,

operating in and against the sides of the said slots, relieve the jerking or straining that would otherwise be upon the junction-pivots of the compound levers or the levers themselves, and thus facilitates the rocking movement of the platform upon the levers; and in addition to this the platform is restored to its proper position above the rails after being depressed by the trains by the weights connecting with the shafts, causing it to ascend, which brings the projecting ends of the rods in contact with the under side of the rails, and thus arrests the further progress of the platform upward.

Another feature of my invention is in the manner of retaining the platform in a depressed position in the event of an express-train coming along, or otherwise, by a man in attendance pushing the main rocking shaft around by a lever and locking into a peculiar spring upright plate.

To enable others skilled in the art to make and use my invention, I will proceed to describe its construction and operation.

A is the rocking rail-platform, constructed of two doubly-inclined rails, and framed together at their ends and center by the transverse rods *a a a*. The rods *b b b* are for bracing and keeping the rails steady and straight.

The platform as constructed is placed between the rails of the track at the point needed for the supplying of trains with water. A suitable excavation of the ground thereat is first made sufficiently to receive the platform and the machinery connected therewith for operating it. The ends of the excavation are properly walled or planked up. The track-rails *c c* at this point are set on stout wooden bed-sills *B B*, which form the sides of the excavation and support the platform machinery.

In the construction of the rails of the platform a solid rib is forged onto wide side pieces, about two inches square, and one inch from the top edges of the same. A slight depression is made thereon by swaging the top surfaces so as to receive the flange-shape of the wheels, which leaves a guard, against which the flanges of the car-wheels run, and thereby obviates all danger of the train running off the track in the event of the platform not being depressed.

C C C are the compound levers. They con-

sist of two levers joined together by pivots *d d*. (See Fig. 2.) The upper levers are placed immediately close to the rails of the platform and the transverse end and center rods passed through them, and thence through the rails of the platform, from which they project into slots *D D D* cut out of the bed-sills on the inside, and immediately under the track-rails, having friction-rollers *e e e* on their ends. The lower levers connect with the rocking shafts *E E E* by their passing through them and then made rigid and permanent thereto.

The upper levers are allowed a free-and-easy movement in their connection with the transverse rods.

The slots in the bed-sills are so constructed as to allow the friction-roller ends of the transverse rods operating therein to have a slight bearing around on the sides, so as to obviate any tendency to jerking or straining of the levers on the pivots, and thus give an easy and steady movement to the platform.

The transverse rods are placed in a straight line, whereby, on the ascension of the platform caused by the weights subsequent to its depression by the trains, the ends of the rods, coming in contact with the under side of the rails, are thereby prevented going any farther, allowing them to go sufficiently above the track-rails to receive the force and weight of the car-wheels. In this way the platform is adjusted to its original position, after being depressed, with a steadiness and uniformity that renders it practicable and unobjectionable in comparison with those methods heretofore in use for adjusting it in this respect.

F F are weights attached to levers *f*, and so arranged on the shafts as to counterbalance the weight of the platform, and thereby cause it to ascend on every depression made by the weight of the car-wheels of the train.

The center shaft, as will be observed, extends out sufficiently from the bed-sill of the track to operate a pump, one of which, *G*, is shown. (Seen clearly in Fig. 2.)

H represents the tank; *g*, the upright stand for supporting the same, and *I* the well. The pump-tubing is carried up from the well into the tank, the latter having therein a pipe, *J*, leading to the well, for returning the superfluous water to the same, and thus prevent its running over the tank when filled.

It is intended that the platform shall operate three pumps through three rocking-shafts connecting therewith, one of which shaft and pump, as connected together and above referred to, is considered all that is necessary to show. The shafts, as mentioned heretofore, pass through the bed-sills and are supported at the terminus of their extension beyond the bed-sills by upright plates, in which they are made to turn or move around, as well as in the bed-sills.

The center shaft, as will be seen, has a short arm, *h*, arranged thereon, which connects with the rod *h'*; which, in turn, connects with the

fulcrum-lever *h''* on the tank-stand, for operating the piston-rod of the pump. The other two pumps are arranged in the same manner in their connection with the shafts, and operate in the same way.

To throw the platform down and retain it in that position, a lever, *I*, is attached to the shaft (seen clearly in Fig. 3) alongside of an upright plate, *I'*, which is so constructed as to have a spring-catch or other equivalent arrangement, so that when the lever is pressed down far enough against the side of the spring it is caught under the catch part of it and there held fast, and the platform is thus locked down out of the way in the event of an express-train coming along. By pushing the lever one side the platform is brought up again.

The platform may be kept down by the locking arrangement, out of the way of such trains that do not stop and take water, by a man whose duty it shall be to attend to the same.

The idea of the operation is this, as practically demonstrated. A train stopping at the tank to take water, a switch or station man, or one of the brakemen of the train, unlocks the platform, and it is ready to work as soon as the train moves off. It shall be the duty of the engineer of the train not to move his train more than two miles per hour until he has passed the length of the train. In fact, he cannot make much more than that time any way. This speed will give eleven strokes per minute to each pump, which will throw two barrels of water to each car into the tank from a well thirty feet deep, or raise water from a well thirty feet deep into the tank. When the last set of trucks in the train comes onto the platform, the brakeman or the man tending the lock fastens the platform down out of the way of the next train, if it be an express-train, and the man, if he be a brakeman, steps onto his train and goes on; and the train that has taken the water has, perhaps, pumped twice as much water into the tank as it took into its tender.

Having thus fully described my invention, what I claim therein as new, and desire to secure by Letters Patent, is—

1. The rail-platform *A*, operating on a series of compound levers, *C C C*, and so connected with the rods *a a a* of the platform and the shaft *E E E* as to impart, by means of the passage of a train of cars, sufficient motion thereto to operate one, two, or three pumps, as may be desired, substantially in the manner and for the purpose as herein set forth.

2. The rods *a a a* of the platform, constructed with friction-rollers *e e e* on their ends, and operating in slots *D* in the bed-sills *B* under and against the rails, so as to give the proper direction and position to the platform in its elevation and depression, substantially in the manner and for the purpose as herein set forth.

3. Depressing the rail-platform and retaining it in that position by means of the lever *h*

on the shaft being locked into the upright spring-plate *i* by the brakeman or man in attendance, substantially in the manner and for the purpose as specified.

4. The fulcrum-lever *h''*, vertical rod, and lever connecting therewith, in combination with the shaft *E*, substantially in the manner and for the purpose as herein specified.

5. The weights *F F* and levers *f f* on shafts,

as arranged to elevate the rail-platform on every succeeding depression of it by the cars of the train when passing thereover, substantially in the manner and for the purpose as specified.

CHAS. L. STEVENS.
